United States Patent Office

Des. 178,525
Patented Aug. 14, 1956

178,525

BAROMETER

Stephen E. Laszlo, Brooklyn, N. Y.

Application June 6, 1955, Serial No. 36,383

Term of patent 14 years

(Cl. D52—7)

FIG. 2.

FIG. 1.

Figure 1 is a front view of a barometer showing my new design; and

Fig. 2 is a side elevational view thereof.

The characteristic features of the design reside in the dial portion shown in full lines.

I claim:

The ornamental design for a barometer, as shown and described.
